(57) **CLAIM**

I claim the ornamental design for a gear measurement template, as shown and described.

DESCRIPTION

FIG. 1 is a straight front view of the invention;

FIG. 2 is a straight rear view thereof;

FIG. 3 is a perspective front view thereof;

FIG. 4 is a rear perspective view thereof; and,

FIG. 5 is a straight front view with environment included. Dashed lines are used to show the environment and other shading lines are used, neither of which comprise any of the claimed invention.

1 Claim, 5 Drawing Sheets
